UNITED STATES PATENT OFFICE.

JOHN F. FOLZ, OF PHILADELPHIA, PENNSYLVANIA.

COMBINED FLAP RETAINER AND MATCH RETAINER.

Application filed August 13, 1925. Serial No. 49,875.

The object of my invention is to devise novel means for retaining in closed position the ends or flaps of packages or containers, and, while not limited to such use it is especially adapted to retain in closed position the end flaps of cigarette packages and also, if desired to carry the matches.

With the above and other objects in view, as will hereinafter more clearly appear, my invention comprehends a novel construction of a flap retainer which may also serve as a match container.

It further comprehends a novel clamping device, consisting of a strip of material having means to engage the flap or end closure of a package or box to retain such parts in their closed condition to prevent the accidental removal of articles contained in the package.

Other novel features of construction and advantage will hereinafter more clearly appear in the detailed description and the appended claims.

For the purpose of illustrating the invention, I have shown in the accompanying drawing a typical embodiment of it, which, in practice, will give reliable and satisfactory results. It is, however, to be understood that this embodiment is typical only and that the various instrumentalities of which my invention consists can be variously arranged and organized, and that the invention is not, therefore, limited to the precise arrangement and organization of these instrumentalities as herein set forth.

Figure 1 is a top plan view of a flap and match retainer embodying my invention, the package being shown in outline.

Figure 2 is a bottom plan view of the retainer seen in Figure 1.

Figure 3 is a section on line 3—3 of Figure 1.

Figure 4 is a top plan view of another embodiment of my invention.

Figure 5 is a perspective view of another embodiment of my invention.

Figures 6 and 7 are end elevations of other embodiments of my invention.

Figure 8 is a top plan view of another embodiment of my invention.

Figures 9 and 10 are, respectively, side elevations of other embodiments of the invention. Fig. 11 is a partial end view of Figure 8.

Similar numerals of reference indicate corresponding parts.

Referring to the drawings:—

In the packaging of cigarettes, they are ordinarily placed in a paper package consisting of an inner lining of paper, an outer covering of foil, and an outer label. The ends of the lining and foil are folded inwardly to form flaps which at one end are secured in closed position by adhesive and at the opposite end by a revenue stamp.

After an end flap has been once opened, no means are provided for retaining the flap closed, so that, after the opened package has been placed in the pocket of the user, the cigarettes work out of the package and the tobacco in the cigarettes work out of the ends of the cigarettes and many of them are thus rendered useless.

In the embodiment of my invention illustrated in Figures 1, 2 and 3, 1 designates the packages having any desired or conventional construction of end closures or flaps. 2 designates the retainer, the body portion of which extends longitudinal and terminates in the bent ends 3 which are spaced apart the proper distance to engage the end flaps or closures of the package to retain them in closed position. 4 designates a book match package which is secured to the retainer by a clip 5 so that the book match package is integral with the retainer.

The retainer 2 is slipped from the package, a cigarette withdrawn, and lighted. The flap is then closed, and the retainer is then closed, and the retainer assembled with the package to form a flat package with the flaps in closed position.

The retainer 2 is preferably formed from a single piece of material, as is the retainer 6 in Figure 4, wherein the strip of which it is formed is bent lateral as at 7 and then downwardly as at 8 upon itself to form a head which embraces a side of the package. The retainer 6 is secured to the book matches 9 by clips 10 and the free ends terminate in flap closing portions 11, similar to those seen in Figure 1.

It is also within the scope of this invention to use two substantially U-shaped retainers 12, disposed at right angles to each other and passing through and fixed to a book match package 13, as seen in Figure 5.

It is also within the scope of my invention to have a substantially U-shaped retainer 14 provided with an exterior pocket 15, fixed thereto in any desired manner, for example by soldering or swaging, see Fig-

ure 6. In Figure 7, the construction is the same as that shown in Figure 6 except that the pocket 17 is secured to the inner face of the body portion of the retainer 18. The 5 free ends of the body portion of the retainer seen in Figures 7 and 8 terminate in flap retainers.

In the embodiments seen in Figure 8, the 10 retainer 19 consists of a substantially U-shaped strip which intermediate the ends of its body portion is looped outwardly to form a grasping portion 20 for manipulating the retainer.

The retainer can be secured to the cigarette 15 package by the label, or by an additional strip of material 21 secured around or to the package by adhesive. This strip 21 may have an opening 22 through which the grasping portion 20 of the retainer passes, or it may be of such material that, when 20 relative rotation of the strip and package takes place, it will puncture the strip.

In Figure 9, the retainer consists of an 25 L-shaped plate 23 to receive the package and having one end laterally deflected to form a flexible or resilient flap retainer 24.

In Figure 10, the retainer is rotatably 30 carried by the package as in Figure 8 but has only one flap retainer 25, and at its opposite end it is bent outwardly as at 26 to form a grasping handle. This retainer may be secured to the package by the label or by an additional strip 27 secured to or 35 around the label.

In all the forms of my invention as herein 40 shown, the retainer may be formed of wire or of bands having any desired contour in cross section and of any desired size or width and may serve as a carrier for the

book matches and if desired form, in many 40 cases, a unit of structure therewith.

It will now be apparent that I have devised a new and useful combined flap 45 retainer and match retainer which embodies the features of advantage enumerated as desirable in the statement of the invention and the above description, and that while I have, in the present instance, shown and described a preferred embodiment thereof which will give in practice 50 satisfactory and reliable results, it is to be understood that this embodiment is susceptible of modification in various particulars without departing from the spirit or scope of the invention or sacrificing any of its 55 advantages.

Having thus described my invention what I claim as new and desire to secure by Letters Patent, is:—

1. The combination with a cigarette 60 package having an inner lining, an outer foil, and a label exterior of the foil, of a flap retainer comprising a strip of material relatively movable with respect to the package and contacting with the label, one end 65 of said retainer being deflected to engage an end flap of the package to retain it in closed position.

2. The combination with a cigarette 70 package having a strip surrounding it, of a flap retainer passing beneath said strip and having deflected ends to engage the end flaps of the cigarette package, said retainer having a deflected portion passing 75 through said strip to form a grasping handle to cause a partial rotation of the flap retainer.

JOHN F. FOLZ, D. D. S.
